PROSTHESIS CONSTRUCTION

Walter Wisbrun, Cleveland Heights, Ohio

Application July 28, 1950, Serial No. 176,459

11 Claims. (Cl. 3-6)

1

Foot and leg prosthesis construction as commonly known is inadequate. First, it does not take account of or accommodate to the peculiar rotating or oscillating motion which the leg performs in locomotion. Accordingly, friction of the stump in the socket is prone to cause discomfort. Second, it lacks capability to provide the throw or centrifugal power which is concerned in the effortless automatism and the gracefulness of the human gait. These defects have arisen from lack of consideration of the structure and intrinsic motions of the normal foot. An adequate prosthesis can not disregard the peculiarities in the foot and leg relationship in structure and functioning. Ease and comfort in walking are involved and should not be sacrificed. In the present invention, the conditions imposed in locomotion are taken account of, and a construction is made possible by which amputees may walk with a sense of security and ease and with comfort not ordinarily thought possible with artificial structures. Other objects and advantages will appear from the following description.

To the accomplishment of the foregoing and related ends, the invention, then, comprises the features hereinafter fully described and particularly pointed out in the claims, the following description and the annexed drawings setting forth in detail certain illustrative embodiments of the invention, these being indicative, however, of but a few of the various ways in which the principle of the invention may be employed.

In said annexed drawings:

Fig. 1 is a plan view of a prosthesis in accordance with the present invention;

Fig. 2 is a vertical section, on slightly larger scale, taken on a plane substantially indicated by line VIII, Fig. 1;

Fig. 3 is a transverse section taken substantially on line IX, Fig. 2;

Fig. 4 is a transverse section taken substantially on line X, Fig. 1; and

Figs. 5, 6 and 7 are views generally analogous to Figs. 1, 2 and 4, showing a slight modification.

For an understanding of the invention it is necessary to first briefly refer to some peculiarities of the anatomy of the foot. The peculiar components of the normal foot, which are essential for the effortless and graceful character of the human gait, involve: First, upward and downward rotation of the first metatarsal bone about the sagittal axis of the sub-talar joint; second, rotation about the vertical axis of this articulation, creating centrifugal power; and third, arrest of the centrifugal motion converting it into

2

propelling motion. These factors are taken account of in prosthesis construction, as illustrated, referring first to Figs. 1-4. Here, a leg post L from a socket of any desired form is articulated to a foot plate made up of a steel plate 3 having some resiliency, and with cushioning rubber 4 forming a generally foot-like contour. Between the leg post and the foot plate are two joints. Articulating with the foot plate is an intermediate post portion 5 which has a forward extension 6 terminating in a cylindrical head 7 which is mounted in the assemblable bearing 8 suitably secured to the plate 3. The composite bearing allows assembly such that the ends of the cylindrical head 7 are overhung by the bearing structure and the joint is held against separation, while allowing a limited rocking motion of the foot plate on the member 5, within the limits of the cut-away margins of the plate 3 and bearing. It is to be especially noticed that a peculiarity of this joint is that it is diagonally oriented with respect to the toe-heel axis. That is, the outer end of the cylindrical head 7 is further forward than the medial or inner end. This peculiar orientation of the joint gives a result that when the foot plate is tipped down at the toe-end, it is also moved inwardly within the limits of the movement, and when the foot plate is reversely rocked, the toe-end is thrown upwardly and outwardly. The importance of this will appear from the description further on. A spring 10 in a socket in the member 5 and bearing against the plate 3 thereunder, normally tends to urge the foot plate in the position with the toe-end in its elevated phase.

Between the leg post L and the member 5 is a joint for limited rotation on a vertical axis. This may be formed for instance on the order of an assemblable joint with an extension head 12 integral with the member and of T-form. The lower end of the leg post L is closed except for a transverse slot 14 which is of dimensions to allow the T-head 12 to slide through when the foot plate is turned transversely. Thus, assembly of the foot plate with its attached post-member 5 can have the T-head inserted through the receiving slot 14 when in transverse position, and on then turning the foot plate back to normal toe-forward position the T-head 12 rides on the annular shoulder 15 of the lower end of the leg post L, and disengagement of this joint would be possible only if the foot were to be turned back transversely such as to register the T-head 12 with the entry slot. Such disassembly is prevented by a stop-screw 16 which may be set into

a tapped receiving hole in the head 12. A transverse slot 17 in the leg post L allows a limited oscillatory movement of screw 16 for the swing of the toe-end outwardly and medially.

As seen, the structure so far described permits a limited rotary or oscillatory movement at the joint between L and member 5, and a limited rocking movement at the diagonal joint 7, 8, in the foot plate. In walking, as the heel strikes the floor, the foot plate is rocked, against the spring 10, on the diagonal joint 7, 8, and the toe-end is immediately positioned properly for progressively receiving the weight of the body, and the extension 6 of the post member 5 comes against the abutment 20 which is secured to the plate 3, and the pressure is transmitted to the forward portion of the foot plate. At the same time, a substantial arm 22 suitably secured to the leg post L, is swung or rotated by the leg post inwardly over, and depressing resilient member 23, to a position above the abutment 20, and pressure is applied through the member 22 to the abutment and foot plate. This motion is seen to result from the swing of the stump and leg movement, transmitted through the leg post L, and is possible by the limited rotating joint between L and post member 5. The resilient member or spring 23 has a hook-shape end, Fig. 4, which acts as a spring buffer as the arm 22 is thrown against it, and the limit of the transverse slot 17 in the leg post L, Fig. 3, then determines the final limit of throw. As aforesaid, the plate 3 has some resiliency, and with the weight centered on the toe portion as in this phase of the step, with the beginning of the next phase as the weight is lifted, the plate exerts some downward thrust resiliently, and assists in the movement of the foot from the floor. In this, by reason of the diagonal orientation of the rocker joint in the foot plate, the toe end now moves up and outwardly for the swinging phase of the step, and the spring 23 inclined and stressed under the member 22 now urges the latter outwardly from over the abutment 20.

In the form shown in Figs 5, 6 and 7, the foot plate structure including the top or cover plate 3, and the attached rubber portion 4, and the diagonally-oriented rocker 7, 8, are the same as afore-described in connection with Figs. 7, etc., also, the leg post or stem L and the rotary joint with the T-head 12, and the limit screw 16, are the same. The intermediate member 5' insofar as partially housing the spring 10, is also the same, and likewise the connection to the diagonal joint member 7. Extending forwardly from the leg post member however is an arm 22', at its forward end which carries an anti-friction roller 25 suitably mounted for free rotation, and in the relative movement as the foot plate rocks on the diagonal joint, the anti-friction roller may travel, in a limited range of movement involved, on the spring member 23' which is secured at one end to the outer portion of the foot-plate. This spring normally tends to rise, and by its inclined positioning tends to swing the arm 22' outwardly, except when pressure is applied by the inclining leg post or stem L in locomotion. That is, in this phase, the arm 22', by the relative rocking in the joint 7, 8, occupies a position relative to the foot plate, as in Fig. 5, whereby the force of the body weight and forward motion may be directed in part through the arm 22' to the forward portion of the foot. Then, with the completion of the stance phase, as the weight is eased and the foot is lifted from the floor, the spring 10 at the

heel portion immediately rocks the foot plate raising the toe upwardly and outwardly for the swinging phase of the step.

By use of graphitized bearing members, problems of lubrication are eliminated. A rubber insert 27 on the abutment 20, Fig. 2, also may cushion and eliminate noise. A rubber facing may be employed on the spring members 23, 23'.

It is usually preferred to provide a slit 28 in the forward end of the foot plate. Where this is done, a more effective resilient up-thrust is attained when the weight of the body is eased from the foot and the foot is in the stage of being lifted from the floor.

15 The construction, as noticed, provides foot movements in locomotion which automatically, as the heel strikes the floor, set the foot plate in proper position to receive and bear the weight from heel to toe, and then as the weight is eased and the foot lifted for the swinging phase, the foot plate is automatically swung upwardly and outwardly. Naturalness of gait is thus inherent in the operation of the structure, and the user is relieved from sensations of discomfort at the 20 stump, and insecurity in the respective swinging 25 and stance phase of stepping.

Other modes of applying the principle of the invention may be employed, change being made 30 as regards the details described, provided the features stated in any of the following claims, or the equivalent of such, be employed.

I therefore particularly point out and distinctly claim as my invention:

1. In prosthesis construction, a leg stem, a foot- 35 plate, an intermediate member between said leg stem and said foot-plate having a forwardly and downwardly extending portion terminating in a diagonally oriented bearing member of generally cylindrical form, a receiving bearing overhanging the ends of the latter in the foot-plate and permitting limited rocking movement, a general cover plate on the foot-plate to which said receiving bearing is secured, a longitudinal slit in the forward end of said cover plate, a T-head extension at the top of said intermediate member, 40 a shoulder in the lower end of the leg stem with partial interruption by a slot to receive said T-head when the foot-plate is turned transversely, thereby forming a rotary joint between the leg stem and the intermediate member, a limit-screw set through a horizontal slot above 45 said shoulder and the leg stem and into the T-head to limit the extent of rotary movement, a spring between the base of said intermediate member and the subjacent cover plate, an arm secured to the leg stem and extending forwardly over the foot-plate, and a spring with one end secured to the outer edge of the foot-plate and extending in under said forwardly extending arm.

2. In prosthesis construction, a leg stem, a foot- 50 plate, an intermediate member between said leg stem and said foot-plate having a forwardly and downwardly extending portion terminating in a diagonally oriented bearing member of generally cylindrical form, a receiving bearing overhanging the ends of the latter in the foot-plate and permitting limited rocking movement, a general cover plate on the foot-plate to which said receiving bearing is secured, a T-head extension at the top of said intermediate member, a shoulder in the lower end of the leg stem with partial interruption by a slot to receive said T-head 55 when the foot-plate is turned transversely, thereby forming a rotary joint between the leg

stem and the intermediate member, a limit-screw set through a horizontal slot above said shoulder and the leg stem and into the T-head to limit the extent of rotary movement, a spring between the base of said intermediate member and the subjacent cover plate, an arm extending forwardly from said leg stem over the foot-plate, an anti-friction roller in the free end of said arm, and a spring with one end secured to the outer edge of the foot-plate and extending in under said roller.

3. In prosthesis construction, a leg stem, a foot-plate, an intermediate member between said leg stem and said foot-plate having a forwardly and downwardly extending portion terminating in a diagonally oriented bearing member of generally cylindrical form, a receiving bearing overhanging the ends of the latter in the foot-plate and permitting limited rocking movement, a general cover plate on the foot-plate to which said receiving bearing is secured, a T-head extension at the top of said intermediate member, a shoulder in the lower end of the leg stem with partial interruption by a slot to receive said T-head when the foot-plate is turned transversely, thereby forming a rotary joint between the leg stem and the intermediate member, a limit-screw set through a horizontal slot above said shoulder and the leg stem and into the T-head to limit the extent of rotary movement, a spring between the base of said intermediate member and the subjacent cover plate, an arm extending forwardly of the leg stem axis allowing end movement with relation to the foot-plate and capable of transmitting pressure to the foot-plate in front of the rocker-joint when the leg stem inclines forward in locomotion, and a spring with one end secured to the outer edge of the foot-plate and extending in under said forward arm.

4. In prosthesis construction, a leg stem, a foot-plate, an intermediate member between said leg stem and said foot-plate having a forwardly and downwardly extending portion terminating in a diagonally oriented bearing member of generally cylindrical form, a receiving bearing overhanging the ends of the latter in the foot-plate and permitting limited rocking movement, a general cover plate on the foot-plate to which said receiving bearing is secured, a T-head extension at the top of said intermediate member, a shoulder in the lower end of the leg stem with partial interruption by a slot to receive said T-head when the foot-plate is turned transversely, thereby forming a rotary joint between the leg stem and the intermediate member, a limit-screw set through a horizontal slot above said shoulder and the leg stem and into the T-head to limit the extent of rotary movement, a spring between the base of said intermediate member and the subjacent cover plate, an arm secured to the leg stem and extending forwardly over the foot-plate, and a spring with one end secured to the outer edge of the foot-plate and extending in under said forwardly extending arm.

5. In prosthesis construction, a leg stem, a foot-plate, an intermediate member between said leg stem and said foot-plate having a forwardly and downwardly extending portion terminating in a diagonally oriented bearing member of generally cylindrical form, a receiving bearing overhanging the ends of the latter in the foot-plate and permitting limited rocking movement, a general cover plate on the foot-plate to which said receiving bearing is secured, a limited motion rotary joint between said leg stem and said inter-

mediate member, an arm extending forwardly of the leg stem axis allowing independent movement with relation to the foot-plate and capable of transmitting pressure to the foot plate in front of the rocker joint when the leg stem inclines forward in locomotion, and a spring with one end secured to the outer edge of the foot plate and extending in under said forward arm.

6. In prosthesis construction, a leg stem, a foot-plate, an intermediate member between said leg stem and said foot-plate having a forwardly and downwardly extending portion terminating in a diagonally oriented bearing member of generally cylindrical form, a receiving bearing overhanging the ends of the latter in the foot-plate and permitting limited rocking movement, a general cover plate on the foot-plate to which said receiving bearing is secured, a limited motion rotary joint between said leg stem and said intermediate member, and an arm extending forwardly of the leg stem axis for independent movement with relation to the foot-plate and transmission of pressure to the foot-plate in front of the rocker-joint when the leg stem inclines forward in locomotion.

7. In prosthesis construction, a leg stem, a foot-plate, an intermediate member between said leg stem and said foot-plate having a forwardly and downwardly extending portion terminating in a diagonally oriented bearing member of generally cylindrical form, a receiving bearing overhanging the ends of the latter in the foot-plate and permitting limited rocking movement, a general cover plate on the foot-plate to which said receiving bearing is secured, a longitudinal slit in the forward end of said cover plate, and a rotary joint between said leg stem and said intermediate member including a T-head extension on said intermediate member and a shoulder in the lower end of the leg stem with partial interruption by a slot to receive said T-head when the foot-plate is turned transversely.

8. In prosthesis construction, a leg stem, a foot-plate, an intermediate member between said leg stem and said foot-plate, a rotary joint between the leg stem and intermediate member including a T-shaped head on the intermediate member and a shoulder in the adjacent end of the leg stem with partial interruption by a transverse slot to receive said T-shaped head when the foot-plate is turned transversely, and a limit screw to prevent disengagement and allow limited rotary movement.

9. In prosthesis construction, a leg stem, a foot-plate articulated to said leg stem by means including a rocker-joint, an arm extending forwardly of the leg stem axis allowing independent lateral movement with relation to the foot-plate and capable of transmitting pressure to the foot-plate in front of the rocker-joint when the leg stem inclines forward in locomotion, and a spring with one end secured to the outer edge of the foot-plate and extending transversely under the end of said forward arm adjacent the foot-plate.

10. In prosthesis construction, a leg stem, a foot-plate, articulating means therebetween permitting relative movement of the forward end of the foot-plate upwardly and outwardly, and downwardly and inwardly, an arm extending forwardly of the leg stem axis allowing independent lateral movement with relation to the foot plate, and transverse spring means pressed by said arm in inward position and urging said arm outwardly on release.

11. In prosthetic construction, a leg stem, a foot member including a resilient steel plate having a longitudinal slit in its forward end separating spring sections unconnected other than to the said plate, and joint-means between said foot member and said leg stem.
